UNITED STATES PATENT OFFICE.

SAMUEL CHASE, OF LONG BEACH, CALIFORNIA.

ADJUSTABLE CAGE-SUSPENSION DEVICE.

Application filed August 17, 1925. Serial No. 50,798.

This invention relates to supporting bracket structures and has for its object the provision of a novel device by means of which a bird cage or the like may be readily suspended at any desired elevation.

An important object is the provision of a bracket device which is so constructed and arranged as to be supported from a picture molding, window casing or the like, it being consequently unnecessary to drive any 10 nails or force any other similar securing members into the wall or wood-work to effect the holding action.

Another object of the invention is to provide a supporting bracket structure for the purpose specified which is provided with brace means adapted to bear against the wall or other support at spaced points and provide a sufficiently rigid support for the 20 cage.

A still further object is to provide a device of this character provided with a peculiar novel grip means operable from a remote point whereby to release the suspension element and permit adjustment of the height 25 of the cage with respect to the floor.

An additional object is to provide a device of this character which will be simple and inexpensive in manufacture, easy to 30 install, neat and attractive in appearance, easy to operate, positive in action, efficient and durable in service, and a general improvement in the art.

With the above and other objects and advantages in view, the invention consists in 35 the details of construction, and the arrangement and combination of parts to be hereinafter more fully described and claimed, and illustrated in the accompanying drawings, in which:—

Figure 1 is a perspective view of the complete device, and

Figure 2 is a fragmentary detail section through one of the bracing elements.

Referring more particularly to the drawings, I have shown the device as comprising 45 an angular bracket arm designated generally by the numeral 10, which arm may be constructed from a suitable length of rod, 50 tubing or the like, and of any suitable material. One end portion of this rod is bent into a substantially V-shape as indicated at 11 to define a vertical arm portion 12 terminating at its upper end in a flattened or 55 chisel shaped or edged hook 13 adapted to be engaged over a picture molding indicated

at A, or upon the upper edge of a window casing, door frame or the like. At the other end of the V-shaped bent portion the bracket extends horizontally to provide an arm 60 14 which preferably has its terminal flattened as indicated at 15 and provided with a suitable hole therethrough. The V bend permits the device to come clear of any curtain rod or the like located at a window. 65

To brace this bracket I provide a transverse arm member 16 which is secured thereto in some suitable manner at or near the bent portion 11 thereof. This arm 16 has its end portion formed with bosses 17 having threaded holes therethrough within which are engaged screws 18 carrying rubber or other resilient tips 19 adapted to bear against the wall B at a point somewhat below the molding A. Obviously, the engagement of the two tip members with the wall 70 will act to brace the bracket 10 and cause it to remain fixed in rigid position with the arm 14 extending horizontally out into the room or other place where the cage C is to 75 be suspended.

Formed or secured upon the top of the arm portion 14 of the bracket is an upstanding projection 20 which is forked as shown and within which is pivotally mounted, at 21, a lever 22 which has one end flattened at 23 and located above the flattened end 15 of the arm 14. This flattened end 23 of the lever is likewise provided with a suitable hole registering with the hole in 80 the flattened portion 15 for a purpose to be described. A leaf spring 24 may be interposed between the bracket arm 14 and the lever 22 for normally holding the latter in 85 such position that the flattened end 23 thereof is adjacent the flattened end 15 of the bracket arm.

The cage suspending element consists of an elongated rod 25 which is engaged 90 through the holes in the flattened ends 15 and 23 and which terminates at its lower end in a suitable hook 26 or other equivalent device upon which is suspended the ring D commonly provided at the top of a bird or other cage. The rod 25 is held in any desired vertically adjusted position owing to the fact that the edge of the opening or hole in the flattened extension 23 will bite against the rod in a manner well understood. Whenever it is desired to adjust the height 95 100 105 110 of the cage, it is merely necessary that the operator grasp or pull upon a suitable chain

27 or the like connected with the rear or inner end of the lever 22 to swing the lever into such position that the edges of the hole in the flattened end 23 thereof will no longer bite against the rod 25, subsequently to which the rod may be slid upwardly or downwardly as desired. When the desired position has been obtained the operator releases the pull upon the chain or other flexible member 27 whereupon the spring 24 will return the lever 22 to its original clamping position.

From the foregoing description and a study of the drawings, it will be apparent that I have thus provided a simply constructed and very neat and attractive device for the purpose specified which possesses the great advantage of rendering it unnecessary to drive any nails or provide other holding means in the wood-work or walls of a room for suspending a bird cage or the like. It is believed that the construction, operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim—

35. 1. A device of the character described

comprising an angular bracket member having a hooked portion adapted to be engaged over a picture molding and having an arm portion spaced below said hook portion and adapted to bear against the wall, a spring 40 pressed lever pivoted upon the other end portion of the bracket, the free end of the bracket and said lever being formed with holes, and a suspension rod slidably mounted through said holes and frictionally 45 clamped by said lever, and screw members adjustably engaged through the ends of said brace member and carrying resilient tips.

2. A device of the character described comprising an angular bracket member 50 formed from a single length of resilient material bent near one end into substantially V-shape to define a vertical arm portion terminating in a hook adapted to be engaged over a picture molding, the other end portion of said length of material extending horizontally and constituting a supporting arm, an upstanding projection on said arm near the forward end thereof, an upwardly 55 spring pressed lever pivotally mounted on said projection, the free end of the arm and the free end of the lever being flattened and provided with holes, a flexible member connected with the other end of the lever for effecting operation thereof from a remote 60 point, and a suspension rod engaged through said holes and clampingly engaged by the lever.

In testimony whereof I affix my signature.

SAMUEL CHASE.
